Primary Examiner — Keli L Hill(74) Attorney, Agent, or Firm — Alexander D Raring(57) CLAIM

The ornamental design for an oven, as shown and described.

DESCRIPTION

FIG. 1 is a perspective view as seen from the top, front and right side of an oven showing the new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown are included for the purpose of illustrating portions of the oven that form no part of the claim.
